UNITED STATES PATENT OFFICE

LOUIS Z. LA FOREST, OF ILION, NEW YORK, ASSIGNOR TO REMINGTON ARMS COMPANY, INC., A CORPORATION OF DELAWARE

CASH REGISTER

Application filed May 9, 1925. Serial No. 29,249.

This invention relates to cash registers and accounting machines, and is more specifically adaptable to those types of machines where keys are merely employed for setting certain parts prior to an operation of the operating mechanism so that the set keys may control or determine the extent of operation of the indicating and registering mechanisms.

Broadly an object of the present invention is to provide means whereby the manipulation of some device for permitting the register to be operated will release and permit the return of any keys which may have previously been set.

More specifically it is an object of the present invention to provide an accounting machine, wherein the manipulation of a lever for selecting certain totalizers for operation will condition certain mechanism so that the machine may be completely operated and simultaneously will release any keys which may have been previously incorrectly depressed.

Another object of the present invention is to provide lock controlled means whereby the automatic release of the depressed keys by the manipulation of the selecting lever may be controlled at will.

Still another object of the present invention is to provide a single lock having connections to certain mechanism whereby all the exteriorly operated and accessible manipulative devices may be locked against fraudulent operation.

With these and incidental objects in view, the invention consists of certain novel features of construction and combination of parts, the essential elements of which are set forth in the appended claims and a preferred form of embodiment of which is hereinafter described in reference to the drawings which accompany and form part of the specification.

Of said drawings:

Fig. 1 is an end view in side elevation showing particularly a portion of the driving mechanism, the means for selecting various totalizers for operation and the improved devices for automatically releasing depressed registering keys.

Fig. 2 is a vertical cross sectional view

through the center of the machine showing in detail the mechanism for imparting a differential movement to the actuators for actuating the totalizers, setting type carriers and adjusting indicators.

Fig. 3 is a top plan view of a portion of the machine showing the actuators, the key release shaft and in general, showing the arrangement and spacing of a number of the mechanisms.

Fig. 4 is another vertical cross sectional view taken adjacent the selecting lever, and shows particularly the locking mechanism for the machine controlled by the sequential operation of the lever and one of a series of special keys. The figure also shows the connections from the selecting lever to the release shaft for automatically releasing depressed keys when the lever is operated.

Fig. 5 is a detail view of the special bank of keys showing how the machine is finally released for operation.

Fig. 6 is a partial view in side elevation showing the means for permitting the automatic key release mechanism to become enabled or disabled. This view also shows a supplemental lock for locking all the manipulative elements.

Fig. 7 is a top plan view of the parts shown in Figure 6.

Fig. 8 is a fragmentary sectional plan view showing the devices for simultaneously locking all the manipulative elements and showing a special key for releasing depressed keys.

Fig. 9 is a portion of the clutch together with the member for locking it and the driving devices for the machine.

In the accompanying drawings the invention is shown embodied in a machine of the type which is well known in the market and which is fully shown and described in the United States Letters Patent #580,378, April 13, 1897, issued to J. P. Cleal and F. A. Reinhard; #707,380, August 19, 1902, issued to F. H. Bickford; #703,639, July 1, 1902, issued to Thomas Carroll; #996,814, July 4, 1911, and #1,153,360, Sept. 14, 1915, both issued to E. J. Von Pein and the patent to C. F. Kettering and W. A. Chryst #1,144,418 issued June 29, 1915. This machine is adopt-

ed for illustration, however, only because it seems to lend itself best for this purpose and for explaining the invention and it is the desire not to be limited to this one embodiment of the idea. The invention is one which can be applied in various modified forms and with almost equal facility to a number of other machines known in the art.

Described in general terms the machine 10 comprises a plurality of accounting devices, such as, totalizers, any one of which may be brought into co-operative relationship with a set of actuators, which are differentially controlled by registering keys. The actuators 15 are suitably connected to a set of type carriers and also serve to adjust suitable indicators.

The operating mechanism is normally locked against operation by either a handle 20 or a motor and is prepared for such operation by the manipulation of a member carried by a totalizer selecting lever and is finally released by the depression of one of a series of special keys.

25 Adjustment or manipulation of the selecting lever at the commencement of an item entering operation will return all previously depressed keys so that the keyboard will be clear and a correct registration will occur 30 when the proper keys are then set and the machine subsequently operated.

Machines of the type to which the present invention has been applied are well known 35 in the art and a brief outline of the parts of the machine disclosed in the prior patents mentioned which co-operate with the present improvement will be given. For a detailed description of the other parts of the machine, reference may be had to the hereinbefore 40 fore mentioned patent to Thos. Carroll #703,639, July 1, 1902, as well as the Von Pein Patents #996,814, July 4, 1911, and #1,153,360, September 14, 1915.

45 Framework

Referring now to the accompanying drawings and more particularly to Figs. 1, 2 and 3, the framework of the machine consists of a base 1 on which are mounted the two parallel 50 side frames 2 and also the parallel intermediate support frames 2', the positions and spacing of the latter being best shown in Fig. 3. The frames 2 and 2' are held securely by front and back tie bars 3 and 4 respectively, 55 and the intermediate frames 2' are so designed as to permit the mounting of a plurality of banks of keys in their front curved portions 5.

60 Driving mechanism

Journalled in the frames 2 and 2' is a main drive shaft 6 (Fig. 1) which is adapted to be turned one revolution for each operation of the machine. The method utilized for 65 driving the shaft 6 may comprise either an

operating handle or a prime mover, such as, a motor as will be explained hereinafter. A crank arm 10 attached to the drive shaft 6 serves to rock a transverse rock shaft 12 by means of a link 11. Secured to the rock shaft 12 are a plurality of driving sectors 13 provided with shoulders 1301.

70 Differential mechanism

The differential mechanism is best shown 75 in Fig. 2 and consists of a plurality of segment gears 14 each of which is controlled by a bank of amount keys 85. A detent 86 provided for each bank of keys is one of a standard form and is described in detail in 80 the patent to W. G. Chambers #1,062,767, May 27, 1913. The detent 86 is segmental in form and is loosely pivoted upon the shaft 12 and is provided with inclined lugs 87 engaged by a bevelled face 88 formed on the stems of the amount keys when these keys are depressed, and the detent is thereby lifted against the tension of a spring 89 so that its shoulder 861 rises above the shoulder 91 on a retaining bar 90 which is then drawn rearwardly by a spring 95, thus locking the detent 86 in its upper position since the lower shoulder 861 of the detent will now engage the shoulder 92 formed on the retaining bar 90. The rearward movement of the retaining bar thus causes the keys to be locked 90 in their depressed positions.

The latching devices used in connection with the segments 14 to co-operate with the driving sectors 13 under control of the amount keys are 95 described in the Cleal and Reinhard Patent #580,378, April 13, 1897, and indicated in the drawings by the numeral 1302. The extent of upward movements of the segments 14 is determined by the depressed keys which as is well known in the art serve to unlatch the segments from the driving sectors 13 at the desired points, the sectors 13 then continue to complete their movements independently 100 of the segments 14. The segment 14 associated with each bank of keys meshes with an associated intermediate gear 15 which is secured to one of a series of nested sleeves 16 that surrounds a shaft 17. The sleeves 16 carry, at their outer left ends, actuators 18 which are in the form of segments, one of these segments being shown in Fig. 1. As is well known these segments are provided for 105 the purpose of driving the totalizer elements of the totalizer which has been selected for operation. Each of the intermediate gears 15 meshes with a gear 19 secured to an indicator 20 loosely mounted upon a rod 21, the latter being secured in the side frames 2 of 110 the machine.

Each of the differentially movable segments 14 is provided with a stud 25 which plays in an elongated slot 26 formed in an arm 27, the lower end of which is connected to 115

one of a series of sleeves 28 that surround a shaft 29. As best shown in Fig. 3 the sleeves extend towards the right side of the machine and are provided with segments 30 which adjust type carriers 31 for printing upon a suitable record material.

As shown in Fig. 2 and as explained in detail in the Cleal and Reinhard patent hereinbefore referred to each gear 15 meshes with 10 a gear 1303 which is for the purpose of driving the corresponding totalizer element of what may be designated as the "grand totalizer" to enter the amounts determined by the depressed keys. By the connecting mechanism 15 described in the Cleal and Reinhard patent the differential movements of the segments 14 and the gears 15 and 1303 will be imparted to the grand totalizer elements so that the amounts set up, indicated and printed 20 will be additively accumulated by these elements. These connections form no part of the present invention and therefore need not be described here.

The totalizer selecting lever which is adjustable to a plurality of positions to select any one of a plurality of sub-totalizers carried by a reel is indicated in the drawings (Figs. 1 and 4) by reference character 35 and is loosely mounted upon the rock shaft 12. 25 The lever 35 has a segmental gear portion 36 which meshes with a segmental rack 37 secured to a shaft 38 mounted in the machine left side frame 2. The segment 37 has attached thereto a larger segmental rack 381 30 which meshes with a pinion 39 secured to the totalizer carrying frame or reel 40. By rocking the lever 35 on its pivot different extents the segment 36 will cause the totalizer reel to be rotated correspondingly, thereby bringing any desired totalizer 40' into operative 35 relationship with the actuating racks 18.

The lever 35 is aligned and maintained in its different settings by a plunger 41 (Figs. 1 and 4) which co-acts with an aligning 40 plate 42 provided with notches 43 which register with the plunger 41. The plunger 41 is spring-pressed into one of the notches in the plate 42 by a spring 44 (Fig. 1) through connections which will now be described. 45 The spring 44 normally draws a locking arm 45 downwardly, the arm 45 being fixed to a short shaft 45' which also carries one arm 46 of a pair of arms 46 and 47 which in turn carry a plate 48 by means of the pivotal connections 49 and 50. The arm 47 is pivotally secured to the machine frame 2 by a pin 51 (Figs. 6 and 7) and is joined to the arm 46 by a pin 471 working in an enlarged perforation 461 in the arm 46. As the locking arm 45 55 is normally drawn downwardly the plate 48 will be forced forwardly towards the aligning plate 42 and as the plunger 41 is provided with a bent lug 52 (see Figs. 6 and 7) extending across the front edge of the plate 48 it will consequently be urged into engage-

ment with one of the notches 43 in the aligning plate 42.

The plunger 41 is carried by a bar 53 (Figs. 1 and 4) which is hung from the locking lever 35 in parallel relation by means of parallel links 54 and 55, the outer end of the bar 53 co-acting with a downwardly extending lug 56 of a thumb grip 57 which is pivoted to the lever 35 by a pin 58. By forcing the grip 57 toward the end of lever 35 by a pinching action the lug 56 engages the bar 53 thus moving the plunger 41 out of engagement with the aligning plate 42 so that the unlocked lever 35 may then be set to another desired position determined by the notches 43.

Machines of this type are commonly provided with interlocking mechanism arranged between the totalizer selecting lever and a series of special keys so that in order to unlock the machine these two elements must be sequentially manipulated. The interlocking mechanism which is embodied in the machine disclosed in the patents already mentioned to perform the results just stated will be described in general, but not in detail, since it is well known in the art and described in detail particularly in the patents to E. J. Von Pein #996,814 and C. F. Kettering and W. A. Chryst #1,144,418 June 29, 1915. However, while the interlocking mechanism is shown in the present application it is to be understood that it is not essential to the invention disclosed and the employment of such devices is in no way required to practice the present invention.

Normally the driving shaft 6 is locked against rotation by a locking member 60 (Figs. 1 and 9) which is pivotally mounted upon the back frame 4 by a pin 61 having its downwardly extending portion 62 in the path of a disk 63 carried by one member of a clutch 64. The co-acting member of the clutch is attached to a suitable driving unit, such as an electric motor. The specific construction of the clutch and driving unit is shown and described in detail in the patents last mentioned.

The member 60 has a notch 631 which is engaged by an arm 641 pinned to a rod 65. An extension 66 (Fig. 4) to which is attached a coil spring 67 is also secured to said rod. From the above arrangement of parts it will be clearly seen that the member 60 is always under the influence of the spring 67 and, if it were not restrained by certain mechanism, it would rock upwardly due to the action of the spring to release the operating mechanism of the machine.

Having particular reference to Fig. 4 it will be seen that the rod 65 has attached thereto a relatively short downwardly extending arm 68. A link 69 connects the arm 68 to a second parallel arm 70 fast on a rock shaft 71. A pair of toggle arms 72 and 73 connected to each other by a pin 74 are provided, the

toggle arm 72 being connected to an extension of the link 69 by a pin 75 while the toggle arm 73 is rigidly attached to the machine frame by a short shaft 76.

5 In the normal position of the parts shown in the above-mentioned figure a straight line from the center of pivot 75 to the center of pivot 76 passes slightly above the connecting pin 74 of the two toggle arms and since the 10 arms are prevented from downward movement as will be explained, the locking member 60 is prevented from disengagement from the clutch 64 to release the machine for operation. However, if the toggle were broken by the 15 elevation of the pin 74 the spring 67 would, through the system of levers just described, move the locking member to releasing position.

20 In order to break the toggle by an operation of the thumb grip 57 an arm 77 is provided and made fast to the shaft 45'. This arm, furthermore, normally prevents the toggle from being broken by downward movement of the toggle arms under influence 25 of spring 67. Now it will be seen that when the grip 57 is operated the bar 53 and the plunger 42 will be depressed and through the plate 48 and arm 46 the shaft 45' will be rocked thereby raising the end of the arm 77 30 to engage and raise a roller 78 carried by the toggle arm 73. Rocking of the arm 77 thus serves to rock the toggle arms so that the pivot 74 is lifted above the straight line joining the pivots 75 and 76 and a further 35 movement of the toggle may then be given by the action of spring 67. The further movement of the toggle referred to which is adapted to be caused by the coil spring 67, tends to rock the arm 68 in a clockwise direction (Fig. 4), through the movement of 40 the link 69. The spring 67 cannot move the system of levers further as explained until permitted to do so by the mechanism yet to be described.

45 As hereinbefore stated the link 69 has an upwardly extending arm which is pivoted to the crank arm 70 rigidly mounted on the shaft 71. The shaft 71 extends across the machine, and as shown in Figs. 4 and 5 it 50 is provided in the plane of a bank of special keys 851, with a crank arm 83 having an upwardly extending projection 82. The bank of keys 851 is adapted to finally release the operating mechanism after the toggle 55 has been broken as explained above by devices which will now be described. Each key is provided with a bevelled face 852 which, when the key is depressed engages a face 853 of a lug 854 carried by a segmental detent 81 60 and thereby elevates the detent. A pin 80 is mounted on a radial arm of the detent 81 and in normal position of the parts is directly above the projection 82 of the arm 83. Consequently, when the toggle is raised as above 65 described, by the pinching of the grip 57 of

the lever 35 the spring 67 will move the system of levers, thereby rocking the shaft 71 until the projection 82 engages and is stopped by the pin 80 on the detent plate, (see Fig. 5). However, when one of the special keys is depressed the pin 80 is carried away from the projection 82 and rocks the pawl 82', pivoted to the arm 83, rearwardly so that the spring 67 then immediately moves the various elements connected therewith further, as already described, and releases the machine for operation by rocking the arm 60 out of engagement with the clutch disk 63.

70 It will be obvious that when one of the special keys is depressed after the pinching of the lever the pin 80 is carried above the projection 82 and the spring 67 then immediately moves all the elements connected therewith causing the cutaway section of the crank arm 83 to surround the pin 80 thereby 80 retaining the detent plate 81 in an elevated position and preventing the depressed key 851 from being released.

85 As the machine is shown, therefore, there is a multiple control for the main operating mechanism, that is, to release the mechanism the lever 35 must first be operated to prevent a partial movement of the locking parts and then one of the special keys 851 must be depressed. The advantage of this is to provide a complete control over the movements of the operator inasmuch as it is requisite, in order to release the machine, that the lever be set to select a particular totalizer for operation and then one of the keys 851 must be depressed to provide for indicating some desired characteristic of the transaction being entered. It may be noted incidentally that the pawl 82' serves to compel the above mentioned sequence of operation of the lever 35 100 and the keys 851. Suppose, for example, the reverse order of operation should be attempted, the depression of a key 851 would serve to move the pin 80 on detent 81 over the upper end of pawl 82' and the subsequent 105 pinching of the lever 35 and grip 57 would merely permit a partial movement of the locking elements until the pawl 82' contacted the under side of pin 80. To release the machine it would then be necessary to release the depressed key and then redepress either 110 the same or a different key 851.

Key release mechanism

115 It is customary in machines of the present type to provide means whereby when a key is depressed in error the same may be released before an operation of the machine is begun. This means comprises the following constructions:

120 It will be recalled as hereinbefore stated that when a key is depressed the detent element 86 is elevated to an extent sufficient to permit the retaining bar 90 to spring rearwardly thereby bringing a shoulder 92 130

formed thereon beneath the lower forward end of the detent member to hold the latter elevated in locking position. It will, therefore, be seen that in order to release the depressed key it will be necessary to draw the retaining bar 90 forwardly against the tension of the spring 95 thereby permitting the depressed key to spring outward under the action of its spring and permitting the detent member 86 to drop down to normal position. The forward movement of the retaining bar 90 is effected in the following manner. At its forward end (Fig. 2) each of the retaining bars 90 carries a pin 96. Adjacent each of the pins 96 is a pin 97 mounted on a rock shaft 98 which extends across the front lower portion of the machine. It will be clear, therefore, in order to restore the elevated detent 86 and the depressed key all that is necessary is to provide means to rock the shaft 98 in any suitable manner and this means as commonly provided in this type of machine comprises a lever situated at the right hand end of the machine and projecting through the cabinet so as to be accessible to the operator of the machine. The construction just described is well known in the art and shown in considerable detail in the patent to F. H. Bickford, #707,380, August 19, 1902.

From the description which has just been given it will be noted that in order to enter an amount in the machine it will be necessary to depress the proper amount keys and if the selecting lever should happen to be in the position corresponding to the totalizer to be selected it will be only necessary to pinch the lever 35 and grip 57 and finally to depress one of the series of special keys to release the machine for operation. It will be understood further that there is no predetermined sequence of operation between the selecting lever and the amount keys and they may be depressed in any order.

Usually cash registers are placed in exposed positions in stores and it frequently happens that children and careless persons either intentionally or accidentally operate the keys and thus make a false record. It has frequently happened that a clerk or customer has inadvertently rested his hand or elbow upon the unlocked keys thereby setting them for operation and again producing a false record. Keys which have been depressed in error are not readily discernible and especially so if one of the lowermost keys should be set, and as is usually the case, the operator desires to complete the transaction with a minimum of time and takes it for granted that all keys are at their normal positions prior to registering an amount.

In order to better illustrate this point, an example will now be given. If the operator or clerk desires to enter a transaction of \$5 and the lowest key in the tens of dollars

bank has been depressed in error it will be understood that an amount of \$15 will be entered in the register, indicated and printed upon the record material. If this incorrect registration should be detected by the operator or customer it would be necessary for the clerk to either cancel this registration or credit the records by an amount equivalent to the value of the key incorrectly depressed. This, of course, requires changing of all the records of the various departments and requires lengthy explanations, and in general, considerable annoyance to all the interested persons. However, if it should not be detected the consequences might be more injurious, since if it should be a "rec'd on acct" transaction the party would be credited with more money than actually received by the clerk. If it should be an ordinary cash transaction the totalizer would show an amount greater than the cash actually received by the clerk and deposited in the cash drawer. When the register was balanced that night there would be a deficit which could only be ascertained by checking up the transactions registered in the machine and printed upon the detail strip, which in itself is a laborious task, and it would then be ascertained only if the operator could recall the transaction in which the mistake occurred.

Where the cash register is provided with a single cash drawer for all of the clerks there would be a greater opportunity for dishonesty since the theft in such case could not be readily traced to the dishonest clerk, and the excuse that would be offered for such shortage is that an amount key might have been depressed in error and not detected. Naturally errors of this kind can readily be prevented by requiring the clerk to insure that all the keys are at their normal positions before an amount is registered, but as long as the personal equation enters in the transaction errors of this kind are bound to occur. The present invention overcomes this objection by utilizing a mechanism which is automatic in its character and insures that any incorrectly depressed keys are returned to their normal positions prior to registering the correct amounts. This mechanism is very simple as very few parts have been added or changes made to the old mechanism, and it is remarkably practical and efficient in fulfilling the objects desired. This mechanism will now be explained in detail.

Automatic key release for registering keys

This mechanism comprises a vertically disposed lever 100 (Fig. 6) fulcrumed on a stud 101 secured to the frame 2 of the machine. The lever 100 is bifurcated at its upper end to engage the pin 471 carried by the arm 47 previously mentioned, while its lower end is provided with a portion 103 (Fig. 4) concentric with the pivot 101 and a shoulder 104. The

rod 98, previously mentioned, is provided at its extreme left end with a short arm 105 extending rearwardly and provided with a pin 106 extending in the path of the shoulder 104. 5 From the arrangement of parts just described, it is evident that when the grip 57 of the lever 35 is operated, to release the selecting lever for movement to a different position, or if it is already in the desired position to merely 10 break the toggle as hereinbefore described, it will, through the parallel bar 53, force the plate 48 inwardly carrying with it, by virtue of the arms 46 and 47, the pin 471 and thereby 15 rocking the lever 100 in a counter-clockwise direction about its fulcrum 101. It will then be seen that the shoulder 104 carried thereby will contact with the pin 106 and move it to such an extent as to move the arm 105 sufficiently to rock the rod 98 in a clockwise direction as viewed in Fig. 4. As previously 20 described, the rocking movement imparted to the rod 98 will, through the pins 97 (Fig. 2) and pins 96, move the retaining bars 90 to permit the return of the detents 86 and thereby 25 release any amount keys that might have been depressed in any of the banks. Consequently, this mechanism insures the normal condition of all the keys on the keyboard at the commencement of an operation and before 30 any of the desired amount keys are depressed. Since the toggle is now broken it is only necessary to depress the correct registering keys and then finally operate one of the series of special keys to release the machine for operation. 35 If, during the setting of the keys one should be depressed in error, it would only be necessary to again pinch the lever 35 to again return all the keys to their normal positions.

The provision of such a mechanism also expedites the time required to enter a transaction in the machine in case an error has been made since in the old machine it was necessary to alternately bring the right hand from the keyboard to the special release lever usually located toward the bottom at the right side of the machine and then back again. In the present machine the release of the keys is performed by a manipulation of the selecting lever by the left hand permitting the right hand to be free to depress the amount keys after the keyboard has been cleared for operation.

Locking devices for keys and selecting lever

55 Machines of this particular type are frequently provided with a locking system which is generally adapted to lock the detents 81 and 86 in such a manner as to prevent any depression of the keys in these banks. It will be 60 understood that when the detent 81 is locked the machine is prevented from any operation. Such a safe-guard is generally under the control of the proprietor or an authorized agent so that the machine may be locked up while 65 not in use. This is ordinarily done at the end

of the day's business so that the machine may not be tampered with and any records which have been entered upon the different registering devices may be kept intact. Heretofore no means has been provided to lock the 70 selecting lever as well as the keys and it is an object of the present invention to perform this additional function. The specific construction and a description of the parts employed in the illustrative embodiment to perform this function will now follow: 75

There is provided in the machine plates 110 (Fig. 2) loosely hung from the lower extremity of each of the curved portions 5 of the intermediate frames 2'. Each plate is provided with an approximately right-angled slot 111 and also carries a lug 112 integral with an extension 113 of the plate. All of the lugs 112 (Fig. 8) of the plates 110 normally extend in the path of the fingers 97 which are carried by the rod 98 so that any rearward movement of the fingers will carry the plates 110 in the same direction, and the substantially horizontal portion of the slot 111 will engage the pins 114 carried by the detents 81 and 86, thereby locking the detents against any displacement and consequently the keys from being depressed. When the machine is unlocked and a key is depressed the pin 114 which is carried by the operated detent will be permitted to move up in the vertical portion of the slot 111 so that the lock cannot become enabled while the machine is in a partly operated condition. 90

The manner in which the fingers 97 are 100 moved rearwardly to rock the plates 110 so as to lock the detents against any movement will now be described.

From an inspection of Figs. 6 and 8 it will be seen that a disk 115 carried by a lock barrel 116 is provided with an eccentrically disposed pin 117 which serves to move at times an arm 118 by means of a bifurcation 119 in the arm engaging the pin 117. The arm 118 is pivoted at 120 and carries a downwardly 105 extending portion 121 provided with another bifurcation forming a slot 122 so positioned as to coat with a pin 123 secured to a vertically extending arm 124 pinned to the rock shaft 98. Normally the pin 123 carried 115 by the arm 124 is made to rest against a shoulder 125, formed by the rear wall of the slot 122, by virtue of a spring 126 attached to the arm 124 at one end and fastened to the machine frame 2' at its other end. The arm 121 will normally prevent a counter-clockwise movement of rod 98 (Fig. 6) but will allow a clockwise movement to release the depressed keys. 120

Upon insertion of the key in the lock and giving the barrel a half turn by means of the key, the disk 115 will cause the pin 117 carried thereby to move downwardly carrying with it the arm 118. The movement of the arm 118 will permit the shoulder 125 carried 125 130

thereby to move in a radial line about the pivot 120 permitting the tension in the spring 126 to draw the pin 123 and arm 124 rearwardly, so that the rod 98 will consequently also be rocked rearwardly to permit the fingers 97 to contact with the lugs 112 and rock the plates 110 so as to lock the detents 81 and 86.

Advantage of the rearward rocking of the rod 98 by this means has been taken to lock the selecting lever 35. To this end the shoulder 104 formed on the member 100 has been so positioned that when the rod 98 is rocked rearwardly (Figs. 1 and 4) to effect a locking of the detents 81 and 86, it will bring the pin 106 carried by the arm 105 against the shoulder 104, as shown by the dotted circle in Figs. 4 and 6.

It is apparent from the above description that when the rod 98 is brought to a locking position it will also by means of the arm 105 and pin 106 acting on the lever 100 and through the arms 46 and 47 plate 48 and lug 52 prevent the retraction of the plunger 41 out of the notches 43 and thereby lock the lever 35 and parts attached or connected thereto against any displacement. It will be understood that the rod 98 is at this time held against clockwise rotation (Fig. 6) by the forward shoulder of the slot 122 in the bifurcated member 121.

Disabling mechanism for automatic key release device

As already pointed out the present invention includes the desirable and advantageous protective feature of automatically releasing the keys which feature has been added to the machine disclosed in the patents mentioned hereinbefore, but while this construction is of great value at most times, it may be that during the course of the day for certain reasons which may arise it will be desirable to permit the setting up of an amount prior to the adjustment of the totalizer selecting lever.

Although this may very seldom be required, such a possibility may arise and to take care of such exigencies a lock controlled means has been devised for disabling the automatic key release mechanism. This mechanism is best shown in Figs. 6 and 7.

Referring more particularly to these figures it will be seen that a vertically sliding member 150 is mounted upon the side of the lever 100 by means of pin and slot connections 151, the member 150 being provided with a shoulder 152 which replaces the shoulder 104 previously described and which is normally adapted to contact with pin 106 in a manner similar to the lug 104 as previously explained. In addition, the slide 150 has an off-set portion 153 in which is formed a slot 154. A lock 155 is suitably attached to the side of the machine cabinet 156 (Fig. 7). A

disk 157 is fast to the rear of the barrel of the lock 155 so as to rotate therewith and is provided with an eccentrically disposed pin 158 adapted to extend into the slot 154 formed in the offset portion 153 of the slide 150. It will be seen that the slot 154 is concentric with respect to the pivot 101 so that when a rocking movement of lever 100 by the pinching of the lever 35 and grip 57 takes place it will carry with it the slidable member 150 without any interference with the pin 158 carried by the disk 157.

It will be readily seen that the general operation of the above-described structure is the same as the previously described device, except that an additional lock controlled means has been provided in place of the rigid shoulder 104 to render such a device effective or ineffective at the will of any authorized person. The operation of this means may be briefly described as follows:

As best seen in Fig. 6 the lock is shown in its effective position, that is to say, if the machine were operated with the parts in this position the pinching of the lever would release the amount keys. This is due to the fact that shoulder 152 integral with the slide 150 is substantially of the same formation as the lug 104 previously described. It is apparent therefore that the shoulder 152 will contact with the pin 106 to rock the rod 98 to release the keys when the lever 100 is rocked by the movement of pin 471 in a manner explained hereinbefore.

Assuming now that a key is inserted in the lock 155 and the bolt operated. The disk 157 will bring the pin 158 carried thereby to a position opposite that shown in Fig. 6 and when the pin is moved up in this manner, it will, by means of slot 154, raise the slide 150 upwardly and consequently will carry the shoulder 152 out of line with the pin 106 so that when the rocking of the lever 100 subsequently takes place the shoulder 152 will not strike the pin 106 and no movement will be imparted to the rod 98 to release the keys.

While the parts are thus conditioned it is desirable to provide the operator with some means capable of rocking the rod 98 to release erroneously depressed keys. To this end a suitable push-key 160 is provided (Figs. 6 and 8) and is loosely mounted to move through a perforation 1601 made in the front tie bar 3. An enlarged head 161 is carried at its inward end so as to contact with a lug 162 integral with a collar 163 pinned to the rod 98. From the foregoing it is clear that when the machine is so operated the old system is reverted to for rocking the rod 98 to release the erroneously depressed keys.

It will be noticed that on account of the design of the present parts when the rod 98 is given a rearward movement to lock the keys and selecting lever, it will simultaneously lock the error key 160. The result is that all

the exteriorly located and manually operable devices are locked against improper manipulation.

General summary of operation

- 5 With the foregoing detailed description it is thought that the invention has been clearly described, but in order to coordinate the various features a résumé of the operation of the machine as a whole will now be given.
- 10 19 It will be assumed that one of the clerks desires to enter an amount of \$5.00 in the machine and that the transaction is one which requires the adjustment of the selecting lever 35 to a new position. The clerk will then depress the thumb grip 57 (Fig. 1) so that the lug 56 engages the bar 53 thus moving the plunger 41 out of engagement with the aligning plate 42. Since the lever 35 is now unlocked it may be rocked about its pivotal point 12 so that the segmental gear portion 36 meshing with the segmental rack 37 will rock the segmental rack 381 thereby driving the pinion 39 secured to the totalizer selecting frame 40. This will select the desired totalizer for operation, the reel being aligned in the proper position by the subsequent engagement of the plunger 41 with one of the notches 42 in the aligning plate 43.
- 20 25 30 When the grip 57 of the lever 35 was operated it forced the lug 52 (Fig. 4) carried by the plunger 41 inwardly also forcing the plate 48 inwardly and, through its connection 49 and 50 to the arms 46 and 47, respectively, 35 rocking the shaft 45'. Rocking of the shaft 45' through the arm 77 will raise the roller 78 carried by the toggle arm 72 thereby bringing the connecting pin 74 above the straight line joining the pivots 75 and 76. The spring 40 45 acting upon the arm 66 will then, through the shaft 65 arms 68, 69 and 70 rock the shaft 71 until the projection 82 of the arm 83 engages and is stopped by the pin 80 carried by the radial arm of the detent 81 associated with the bank of special keys.

45 50 55 As previously stated the shaft 65 will be partially rocked, but not sufficiently to release the machine for operation. This, of course, requires the depression of one of the special keys to finally release the machine for operation, but it will be necessary to first depress the proper amount key in order to effect the desired registration.

55 Referring to Fig. 2 when the "five" key in the dollars bank is depressed the camming portion 88 co-acting with the inclined lug 87 in the detent 86 will lift its shoulder 861 from the shoulder 91 on the retaining bar 90 which is then drawn rearwardly by the spring 95. Since the lower end of the detent now engages the higher shoulder 92, formed on the retaining bar, the key will be locked in its depressed position.

60 65 70 In order to release the machine for operation one of the special keys is operated and

this will provide for indicating some desired characteristic of the transaction.

70 When the desired special key is depressed its cam portion will engage the lug formed on the detent 81 (Fig. 5) and will raise the detent so as to carry the pin 80 away from the projection 82 so that the spring 67 can then completely rock the shaft 65 to carry the locking arm 62 (Fig. 9) free of the clutch member 63. This will establish a driving connection between the motor and the driving shaft 6 and it follows that when the shaft 6 is rotated it will, through the link 11 rock the shaft 12 and the driving sectors 13 so that the shoulder 1301 on the dollars sector will on the return stroke of the latter engage a portion of the latch mechanism 1302 so that the extent of movement of the segment 14 which carries the latch mechanism will be determined by the depressed key. The manner of imparting a differential movement to the segment 14, and how through intermediate connections it enters the desired amount in the grand totalizer as well as the selected sub-totalizer and how it sets a related indicator and type wheel is well known in the art and need not be explained here.

75 80 85 It will be assumed that the "one" key in the tens of dollars bank was depressed in error and was not detected by the clerk operating the machine. Without the use of the present invention it will be clear that \$10.00 will be erroneously entered in the machine. By the employment of the improved devices it will be noted that when the operator pinched the lever 35 and grip 57 it rocked the lever 100 (Fig. 4) about its pivotal point since the lever is connected to the arm 46 by the pin and slot connection 471. As the lever 100 was rocked in a counter-clockwise direction about its pivot the shoulder 104 integral with the lever 100 engaged a pin 106 carried by the arm 103 and rocked the shaft 98 in a clockwise direction (Fig. 4). As best shown in Fig. 2 rocking of the shaft 98 will, through the radial pin 97 and pin 96, move the retaining bar 90 forwardly permitting the return of the detent 86 associated with the tens of dollars bank, thereby releasing the ten dollar key.

90 95 100 105 110 115 A modified construction of the lever 100 may be employed so that if it is desired for some reason or other to disable the automatic releasing of the registering keys by pinching the lever a key may be inserted in the lock 155 (Figs. 6 and 7) and operated so that the disk 157 will raise the pin 158 upwardly and by means of the slot 154 raise the slide 150 carried by the lever 100. This will consequently bring the shoulder 152 (similar to shoulder 104 in Fig. 4) out of line with the pin 106 so that even though the selecting lever is again pinched the shoulder 152 will not strike the pin 106, thereby imparting no movement to the shaft 98 to release the

keys. If one should be depressed in error it will be released by simply forcing the "push" key 160 inwardly and through the lug 162 rocking the shaft 98 to perform the functions previously stated.

At the end of a day's business or some other period it is desirable to lock all the externally located and manually operable devices and to this end when it is so desired the bolt of the lock 116 (Fig. 6) may be operated by the turning of an inserted key in the lock. Rotation of the disk 115 through the pin 117 will move the arm 118 downwardly so as to permit the shoulder 125 formed on the arm 121 integral with the arm 118 to move in an arc about the pivot 120 thereby permitting the spring 126 to rock the pin 123 and arm 124 rearwardly. Since the arm 124 is attached to the shaft 98 the latter will be rocked counter-clockwise as viewed in Fig. 6, bringing the pin 106 carried by the arm 105 against the shoulder 152 (or 104 Fig. 4) and locking the selecting lever in its adjusted position, the slot 122 positively preventing forward movement of the parts.

At the same time the lug 162 will be brought against the collar 161 carried by the rearward end of the "push" key 160. This, of course, will lock the error key in its outward position.

While the shaft 98 was being rocked the pins 97 (Fig. 2) coacting with the lugs 112 integral with the plates 110 rocked the plates counter-clockwise as viewed in Fig. 10 so that the pins 92 carried by the detents 81 and 86 co-operate with the substantially horizontal portion of the slots 111 formed in the plates 110. Co-action of the pins 92 with these portions of the slots locks the detents 86 and 81 in their normal position, thus preventing the raising of the detents by the depression of any of the amount or special keys respectively.

For the purpose of illustration a specific form of the invention has been shown in connection with a particular type of register, but it may, however, be applied to any form of machine wherein any manually operable device is operated, either partially or completely to unlock the machine for operation. The manually operable device may be of any form whatever as long as it has connections to the releasing devices for the keys so that when operated it will control the unlocking mechanism for the machine and simultaneously release the depressed registering keys.

As far as applicant is aware he is the first in the art to show this combination and desires to broadly claim the same and it is to be understood that the scope of the invention is not to be limited to the construction shown and described.

While the form of embodiment herein shown and described is admirably adapted to fulfill the objects primarily stated, it is to be understood that it is not intended to con-

fine the invention to the one form of embodiment here shown since it may be embodied in various forms all coming within the scope of the claims which follow:

What is claimed is:—

1. In a cash register, the combination with a normally locked operating mechanism, of a manually operable device for controlling the unlocking of said mechanism, a differential mechanism, a plurality of depressible keys controlling the extent of movement of the differential mechanism by the operating mechanism, and means controlled by the manually operable device for releasing depressed keys preliminary to the operation of the machine.

2. In a cash register, the combination of a manually operable device, an operating mechanism, differential mechanism, a plurality of depressible keys controlling the extent of movement of the differential mechanism by the operating mechanism, and means controlled by the manually operable device for unlocking the operating mechanism and simultaneously releasing depressed keys.

3. In a cash register, the combination with a manually operable device for controlling the selection of a plurality of totalizers, of keys for controlling the extent of operation of the selected totalizer, and means under control of the manually operable device for releasing depressed keys when the manually operable device is manipulated to select a totalizer.

4. In a cash register, the combination with an operating mechanism, of a manually operable device operable as a preliminary to the operation of the operating mechanism, a differential mechanism, keys for controlling the extent of movement of the differential mechanism by the operating mechanism, releasing devices for said keys, and means whereby the manually operable device operates the releasing devices preliminary to the operation of the machine.

5. In a cash register, the combination of a totalizer selecting lever movable to different positions, settable keys, devices releasing keys that are in set position, and means under control of the lever for operating the releasing devices as an incident to the adjustment of the lever from one position to another.

6. In a cash register, the combination of a totalizer selecting lever, a latch for retaining said lever in adjusted position, a plurality of settable keys, devices for releasing keys that are set, and means controlled by the latch for operating the releasing devices.

7. In a cash register, the combination with an operating mechanism of a manually operable device operable as a preliminary to the operation of the operating mechanism, a differential mechanism, settable keys for controlling the extent of movement of the differ-

ential mechanism by the operating mechanisms, releasing devices for said keys, means whereby the manually operable device operates the releasing devices preliminary to the 5 operation of the machine, and lock controlled devices for disabling said means.

8. In a cash register, the combination of a plurality of settable keys, devices for releasing keys that are set, a lever for selecting 10 totalizers, and means carried by said lever whereby said releasing devices may be operated in any position of the lever.

9. In a cash register, the combination of a differentially movable lever for selecting 15 totalizers, means carried by the lever operable as an incident to adjusting the lever to another position, a plurality of settable keys, devices for releasing keys that are set, and connections whereby said means operates the 20 releasing devices.

10. In a cash register, the combination of a lever adjustable to a plurality of different positions, a plurality of settable keys, and a common locking means for locking said keys 25 against depression and the lever against movement, in any of said positions of the lever.

11. In a machine of the class described, the combination of a series of operable and normally 30 arrestable keys, a series of operable but normally unarrestable keys, a differentially movable device, means under control thereof for permitting the arresting of any key of the series of normally unarrestable keys, and 35 means whereby the differentially movable device releases any depressed key of the series of normally operable and arrestable keys.

12. In a cash register, the combination of a plurality of settable keys, devices for releasing keys that are set, a differentially movable lever for selecting totalizers, and means 40 attached to said differentially movable lever for operating the releasing devices.

13. In a cash register, the combination of 45 an operating mechanism, locking devices therefor, a series of amount keys, a series of special keys, a lever, means whereby a predetermined sequence of operation between the lever and one of the special keys is necessary to operate the locking devices, and 50 means whereby the lever releases any of the depressed amount keys.

14. In a machine of the class described, the combination of a totalizer, a set of manipulative elements for controlling amounts to 55 be registered, a preliminarily movable element for conditioning the machine for itemizing operation, and means whereby any displaced manipulative elements for controlling 60 amounts will be restored to normal position by the manipulation of the preliminarily movable element.

15. In a machine of the class described, the combination with a main operating 65 mechanism, of a device normally locking said

operating mechanism against operation, depressible amount keys for determining the amounts to be entered in the machine by the main operating mechanism, an adjustable totalizer selecting element for conditioning the locking device to become released, and means operated by said adjustable element for causing the release of any of the depressed amount keys.

16. In a cash register, the combination of 70 a series of operable keys, means for arresting keys that are operated, of a differentially adjustable manipulative device for selecting various totalizers, and means attached to said device for releasing any arrested key.

17. In a registering machine, provided with a main driving mechanism and a plurality of accounting devices, the combination of a set of normally depressible keys for controlling amounts to be entered into the different accounting devices, a manually operable lever for selecting the desired accounting device for operation, and connections between said selecting lever and the said set of amount keys so that the latter will be released and restored to their normal positions by the manipulation of the selecting lever.

18. In a cash register, the combination of 95 a totalizer selecting lever movable to different positions, settable keys, devices for releasing keys that are set, and means under control of the lever for operating the releasing devices as an incident to the adjustment of the lever from one position to another.

19. In a machine of the class described, the 100 combination of a main operating mechanism, locking means therefor, a set of amount keys, a manipulative element for controlling said locking means, and means for preventing an effective set-up-on said keys prior to operation of said element.

In witness whereof I have signed my name hereto this 6th day of May, 1925.

LOUIS Z. LA FOREST.
